UNITED STATES PATENT OFFICE.

HENRY BRAUNLICH, OF DAVENPORT, IOWA.

LAUNDRY APPARATUS.

1,254,972.

Specification of Letters Patent. Patented Jan. 29, 1918.

Application filed January 14, 1916. Serial No. 72,051.

To all whom it may concern:

Be it known that I, HENRY BRAUNLICH, a citizen of the United States, and a resident of Davenport, in the county of Scott and State of Iowa, have invented certain new and useful Improvements in Laundry Apparatus; and I do hereby declare that the following is a full, clear, and exact description thereof, reference being had to the accompanying drawings, and to the letters of reference marked thereon, which form a part of this specification.

This invention relates to improvements in laundry apparatus and consists of the matters hereinafter described and more particularly pointed out in the appended claims.

The object of this invention is to provide a hand operated laundry apparatus adapted for domestic use, whereby the operation of washing the clothes and the operation of extracting the water from the clothes, may be carried on with different "batches" of clothes at the same time and by means of a single prime moving lever. In carrying out the invention I adopt a water extracting device or wringer of the centrifugal type, which is operated at a relatively high rate of speed and acts as a balance wheel or flywheel for the gearing that operates the washing machine.

The advantages of my improved laundry apparatus will appear more fully as I proceed with my specification.

In the drawings:

Figure 1 is a view in front elevation of a laundry apparatus, made in accordance with my invention.

Fig. 2 is a top plan view thereof.

Fig. 3 is a longitudinal vertical sectional view of the same, the plane of the section being indicated by the line 3-3 of Fig. 2.

Fig. 4 is a transverse vertical sectional view, the plane of the section being indicated by the line 4-4 of Fig. 1.

Referring now in detail to that embodiment of my invention illustrated in the accompanying drawings:—10 indicates a supporting bench which carries at one end a washing machine and at its other end a centrifugal wringer which is adapted to receive the clothing after having been operated upon by the washing machine, to extract the water therefrom. Said bench is made in the form of an open rectangular frame, somewhat elongated, and comprises longitudinally extending side members 11. 11,

and transverse end members 12 and 13 respectively, and supporting legs 14 and 15 arranged in pairs, fixed to said frame at the corners thereof.

Intermediate said end members 13 and 14, said frame is provided with a transverse brace member 16 which also forms a part of the support for the washing machine.

17 indicates as a whole a washing machine which is mounted upon that end of the frame 10 supported by the legs 15, and clips 18 secure the same to the longitudinal members 11, 11, the end member 13 and the intermediate member 16 of said frame (see Fig. 3). Said washing machine comprises a tub body 19 which rests at its bottom, on the top edges of said frame members before mentioned, and the top of said tub body is closed by a stationary top wall part 20 and a lid 21 which is hinged thereto so as to swing in a plane parallel to and adjacent the rear longitudinal member 11 of the frame.

22 indicates the upright operating shaft of the washing machine which is journaled in a bearing sleeve 23 made integral with a bracket plate 24 fixed to the hinged lid 21. Said shaft is concentrically arranged relative to the tub body, into which it depends and is provided on the end within the tub with a dolly or agitator 25. To the top end of said shaft is fixed an upwardly facing bevel gear 26 which meshes with a segmental bevel gear 27 fixed to the inner end of a horizontal rock shaft 28.

The rock shaft 28 extends radially with respect to the tub body, and in a plane parallel to the longitudinal frame members 11, 11, and is suitably journaled in upright standards or bearing arms, 30, made integral with said bracket plate 24. The outer end of said shaft projects beyond the edge of the lid 21 toward the end frame members 12 and has fixed thereto a prime mover lever 29. To the load arm 31 of said lever is operatively connected one end of a link 32, the other end of which is connected to a crank pin 33^a of a large gear 33, journaled on a stud 34 fixed relative to said bracket plate 24. This stud extends parallel with the shaft 28 but is spaced therefrom so as to be located in a plane above and to the rear of the hinged edge of the tub lid 21. It is apparent from the foregoing description, that a rocking movement of the hand lever 29 will be transposed into a continuous

rotary movement of the ear 33 and into an alternating rotary movement of the upright operating shaft 22, by the means hereinbefore mentioned.

5 The legs 14, 14, are projected upwardly so as to terminate in a plane a trifle above that of the top wall of the washing machine and they are there braced and connected together by means of transverse members 35, 36, arranged horizontally and vertically respectively. Fixed to the longitudinal members 11, 11 of the frame adjacent the transverse member 16, are provided upright members 37, 37, which terminate at their top in 10 the plane of the top ends of the legs 14. Said uprights are braced and connected together at their top by means of a transverse member 38. To the transverse members 36 and 38 is fixed a longitudinally extending 15 platform 40 upon which is mounted a centrifugal wringer indicated as a whole by the numeral 41. Said wringer is adapted to extract the surplus water from the clothing after being operated upon by the washing machine 17. The said centrifugal wringer is preferably arranged a trifle back from the front of the bench 10 and comprises an open top cylindrical can or container 42 having a bottom wall which rests 20 upon and is fixed to said platform in any suitable manner. A clothes basket 44 is coaxially arranged within the cylindric wall of said container and is adapted to receive the clothes to be wrung. Said basket is 25 adapted to be rotated at high speed within said container. It comprises an upright cylindric wall 45 of open wire mesh spaced from the upright wall of the container and a bottom wall 46, which is spaced from the 30 bottom wall of the container. Concentrically arranged relative to the basket 44 and fixed to its bottom wall is a depending shaft 47 which extends through and beyond the platform 40. A downwardly facing bevel 35 gear 48 is fixed to said shaft 47 below the platform 40. An antifriction bearing 49 is provided for said basket and to prevent a vertical displacement of said basket and shaft, a clip 50 fixed to the under side of the said platform, is caused to engage a collar 51 on said shaft below the gear 48.

The bevel gear 48 meshes with a like gear 52 fixed to one end of a longitudinally extending shaft 53 which is journaled in suitable bearing brackets 54, 55, depending from the platform 40. The other end of the shaft 53 extends into the vicinity of the washing machine tub and is there provided with a gear 56 which is adapted to be operatively engaged by the large gear 33 before mentioned.

It is apparent that upon rotation of the gear 33 by means of the lever 29 as before mentioned, a continuous rotary motion at 65 a high speed will be imparted to the clothes

receiving basket through the gear 56 on the shaft 53 and the bevel gears 48 and 52 respectively. When the lid 21 is swung about its hinged connection with the stationary top 20 of the tub, so that clothing may be 70 placed therein or removed therefrom, the large gear 33 will be operatively disconnected from the gear 56, as is indicated in dotted lines in Fig. 4. When swung into a closed position, the said gears will again operatively mesh with each other.

The operation of my improved laundry apparatus is as follows: The tub lid 21 is swung about its hinged connection into an open position and the usual suds water 80 placed therein. The clothing to be operated upon is then placed in the tub and the lid closed and locked in this position by the usual means provided therefor, the gears 33 and 56 operatively meshing with each 85 other. The operator then grasps the lever 29 and imparts a back and forth rocking movement thereto. Should the lever happen to be on a "dead center" position relative to the gear 33 and its associated crank 90 pin, the operator may relieve this condition by imparting a slight push or start to the basket 44 of the centrifugal wringer 41. The rocking movement of the lever will cause an alternating rotary movement of the 95 agitator as before described, which will move the clothing through the water in the tub first in one direction and then in a reverse direction. The gear 33 will have a continuous rotary movement imparted to 100 it as before described, which continuous rotary movement is imparted to the gear 56 on the end of the shaft 53 at a high speed owing to the relative sizes of said gears. This rotative movement at high speed is 105 imparted to the basket of the centrifugal wringer, the momentum of which will materially assist in reducing the effort on the part of the operator to rock the hand lever 29. When the clothing in the washing machine is sufficiently clean, the operator unlocks the lid and raises the same. The washed clothing is then removed from the tub and placed in the basket of the centrifugal wringer. While the tub lid is open, other 110 clothing is placed in the tub and the lid again closed and locked. The operator again imparts a rocking movement to the lever 29 and the agitator or dolly will again operate to wash the clothing in the 115 tub. The basket of the centrifugal wringer is now rotating at high speed and under the action of centrifugal force the clothing will closely engage the upright wire mesh wall of the basket. The excess water in the 120 clothing being unrestrained, will be thrown outwardly and through the mesh of the basket to be collected in the container 42 from which it is drained by means of a drain spout 42* (see Fig. 2), into any suitable re- 125

ceptacle to be provided therefor. As before, the basket of the wringer will act as a fly wheel and when loaded will act with a better result than when empty.

5 The clothing after having been operated upon by the extracting device is now ready to be dried and the basket thereof is again ready to receive the clothing operated upon by the washing machine. The cycles or 10 steps are repeated until the entire batch of clothing to be operated upon has been washed and the excess water extracted therefrom as has been heretofore described.

It is apparent that my improved laundry 15 apparatus is advantageous in that two steps of a clothes washing operation may be carried on by a hand operated machine at the same time with the same amount of effort on the part of the operator as has heretofore 20 been expended in carrying out but one of said steps, namely, that of washing the clothes, as the device for removing the excess water from the clothing acts as a balance wheel for the said washing machine 25 and insures a smooth easy operation of the same.

The centrifugal extractor effectually removes the water from the clothing operated upon without damage to the same, even 30 though it be of the finest lace texture. Also no buttons are torn therefrom as always occurs when clothing is passed through an ordinary roll wringer, whether the same be manually or power operated.

35 While in describing my invention, I have referred to certain details of construction and arrangement of parts, I do not wish to be limited thereto except as may be pointed out in the appended claims.

40 I claim as my invention:—

1. A laundry apparatus comprising a bench, a washing machine supported on said bench, a centrifugal extractor supported on said bench in a position adjacent to said 45 washing machine, a prime moving lever common to both said washing machine and to said extractor, means actuated by said lever for operating said washing machine, and means actuated by said lever for operating said extractor.

50 2. A laundry apparatus comprising a bench, a washing machine supported on said bench, said washing machine having an alternating rotary operating member, a centrifugal extractor supported on said bench in a position adjacent to said washing machine, said extractor including a continuously rotary member, a prime moving lever common to both said washing machine and 55 said extractor, means connecting said prime moving lever with said alternating rotary operating member of the washing machine, and means connecting said prime moving lever with the rotary member of said 60 extractor.

3. A laundry apparatus comprising a bench, a washing machine supported on said bench, said washing machine having an alternating rotary operating member, a centrifugal extractor supported on said bench 70 in a position adjacent to said washing machine, said extractor including a continuously rotary member, a prime moving lever common to both said washing machine and said extractor, means connecting said prime moving lever with said alternating rotary operating member of the washing machine, and means connecting said prime moving lever with the rotary member of said extractor, the means connecting said operating 75 lever with said rotary member of the extractor including separable parts whereby the extractor is operated only when the washing machine is operated.

4. A laundry apparatus comprising a 85 bench, a washing machine supported on said bench, said washing machine having a hinged lid and an upright alternating rotary operating member depending through said lid, a centrifugal extractor supported on 90 said bench in a plane above that of the top of the washing machine, said extractor including a rotary member and an upright shaft for driving said member, a prime moving lever common to both said washing machine and said extractor carried by the hinged lid of said washing machine, and means operatively connecting said prime moving lever on the one hand to the upright 95 operating shaft of the washing machine, and on the other hand to the upright shaft of said extractor.

5. A laundry apparatus comprising a bench, a washing machine supported on said bench, said washing machine having a 105 hinged lid and an upright alternating rotary operating member depending through said lid, a centrifugal extractor supported on said bench in a plane above that of the top of the washing machine, said extractor including a rotary member and an upright shaft for driving said member, a prime moving lever common to both said washing machine and said extractor carried by the hinged lid of said washing machine, and 110 means operatively connecting said prime moving lever on the one hand to the upright operating shaft of the washing machine and on the other hand to the upright shaft of said extractor, said means including meshing gears, one carried by said hinged lid 115 and the other by said bench.

6. A laundry apparatus comprising a bench, a washing machine supported on said bench, said washing machine having a 125 hinged lid and an upright alternating rotary operating member depending through said lid, a centrifugal extractor supported on said bench in a plane above that of the top of the washing machine, said extractor 130

including a rotary member and an upright shaft for driving said member, a prime moving lever common to both said washing machine and said extractor carried by the hinged lid of said washing machine, and means operatively connecting said prime moving lever on the one hand to the upright shaft of the washing machine, and on the other hand to the upright shaft of said extractor, said means including a high speed gear carried by said lid and a pinion carried by said bench.

7. A laundry apparatus, comprising in combination with a washing machine, a centrifugal extractor and means for operating the washing machine and the extractor in connected relation, the washing machine having an alternating rotary operating

member and the extractor having a basket adapted to be continuously rotated, a prime 20 moving lever common to both the washing machine and to the extractor, means operatively connecting the lever with the alternating rotary operating member of the washing machine, and means operatively connecting the lever with the rotary member of the extractor, including high speed gearing. 25

In testimony that I claim the foregoing as my invention I affix my signature in the presence of two witnesses, this 16th day of 30 December, A. D. 1915.

HENRY BRAUNLICH.
